Samuel Lieberman, 42 Oak Hill St., Newton Center, Mass.

Filed Jan. 7, 1960, Ser. No. 58,953

Term of patent 14 years

(Cl. D40—1)

FIG. 1

FIG. 2

FIG. 4

FIG. 3

Figure 1 is a top plan view of a housing for a lawn edge trimmer showing my new design;

Figure 2 is a right side elevational view thereof;

Figure 3 is a front perspective view taken from the left side and top thereof; and

Figure 4 is a rear elevational view thereof.

This is a continuation-in-part of my application Serial No. D. 53,899, filed December 24, 1958, now abandoned.

I claim:

The ornamental design for a housing for a lawn edge trimmer, as shown.
